ROLLER VIBRATOR

Ture Evert Andersson, Ljungby, Sweden, assignor to Vibro-Plus Corp., Woodside, Long Island, N. Y., a corporation of Delaware

Application January 27, 1954, Serial No. 406,547

Claims priority, application Sweden January 30, 1953

3 Claims. (Cl. 94—48)

The present invention relates to a mechanical vibrator, i. e. a mechanical device for generating vibrations, of the type comprising a circular roller track along the inside of which a spherical body is adapted to roll while being driven forward or propelled by a driver mounted on a central driving shaft, and the main object of the invention is to provide a mechanical vibrator which is particularly suitable for use with vibrating rollers, while it is capable of withstanding blows and shocks in all directions and is subjected to little wear notwithstanding the fact that it can generate vibrations of high amplitude.

The vibrator according to the invention is mainly characterized in that the inside of the roller track has a groove which serves as a race for the spherical body and has a progressively decreasing depth towards its sides and that the spherical body consists of a loose ball which is adapted to be actuated peripherally by the driver.

The invention also relates to a vibrating roller equipped with a mechanical vibrator according to the invention and which is of the type in which the vibrating roller drum itself carries a roller frame on which is mounted the motor provided for driving the vibration generator, the said motor usually taking the form of an internal combustion engine, and the roller according to the invention is mainly characterized in that the driving shaft of the vibrator is mounted on the roller frame and serves as a supporting shaft for the roller drum, said roller drum being rotatably mounted on eccentric parts of the driving shaft the centres of which are displaced in relation to the driving shaft in a direction diametrically opposite to that of the ball actuated by the driver.

With the foregoing and other objects in view, the invention resides in the novel arrangement and combination of parts and in the details of construction hereinafter described and claimed, it being understood that changes in the precise embodiment of the invention herein described may be made within the scope of what is claimed without departing from the spirit of the invention. It will be further understood that my invention is susceptible of embodiment in many and various forms, some of which are illustrated in the accompanying drawing, and that the structural details herein set forth may be varied to suit particular purposes and still remain within our inventive concept.

Other characteristic features of the invention will appear from the following description of a preferred embodiment of a roller with a vibrator, both according to the invention, illustrated in the accompanying drawings. In the drawing Fig. 1 is a side view of the roller while Fig. 2 is a plan view of the same and Fig. 3 is a sectional elevation of the roller drum taken along the line III—III in Fig. 2. Fig. 4 shows a radial section through the one vibrator in the roller drum, the said section being taken along the line IV—IV in Fig. 3, while Fig. 5 shows the driver structure viewed from the line V—V in Fig. 4. Fig. 6 is a partial section through the roller frame taken along the line VI—VI in Fig. 1, while Fig. 7 is a corre-

sponding partial section through the roller frame along the line VII—VII in Fig. 1. Fig. 8 shows a longitudinal section through the front end of the roller frame viewed from the line VIII—VIII in Fig. 2.

The roller illustrated in the drawings comprises a frame 1 which is preferably assembled from box beams and which surrounds a roller drum 2 which rolls on the ground when the roller is working and serves as a carrier for the frame 1. The shaft of the drum 2 runs transversely of the frame 1 and is located substantially midway of the length of the frame. The front end of the frame is tapered and provided with a towing member 3 at its front end, the said towing member consisting, as shown in Fig. 8, of a piston rod that can move in a tube 4 in the frame, its inner end being provided with a piston-like flange or washer 5 which is actuated from each side by two compression springs 6 and 7 located in the tube 4, and which can absorb the jerks and shocks that may be set up between the roller and the traction device to which the front end 8 of the towing member, shaped as an eyelet, is connected.

The rear part of the frame 1 is formed to a platform 9 which carries a driving motor 10 for the vibrator of the roller drum 2, usually an internal combustion engine. This platform 9 with its motor 10 and any other equipment is balanced by a suitable mass 10' of scrap-iron and/or concrete which is placed in the front part 11 of the frame 1, surrounding the tube 4, the said part taking the form of a box. By means of this balancing arrangement the centre of gravity of the frame is located almost directly under the shaft 12 of the roller drum 2.

The frame 1 is elastically suspended from the shaft 12 of the roller drum 2 by means of yokes 13 which, as may be seen from Fig. 7, are provided with vertical holes 14 for the reception of supporting rods 15 the lower ends of which are provided with a head 16 between the upper side of which and the beams of the frame 1 powerful compression springs 17 are arranged. The springs 17 are enclosed in the frame beams and are thus protected by the latter, and the length of the supporting rods 15 may be regulated by means of nuts 18 threaded onto the upper ends of the supporting rods projecting through the yokes 13. By means of this arrangement the frame 1 is free to move up and down elastically in relation to the yoke 13 and the roller drum 2. Transversally and longitudinally the yokes 13 are supported in relation to the frame 1 by means of plates 19 on the frame, and between said plates 19 and the yokes 13 are provided vibration dampers 21 in the form of rubber cushions secured by vulcanization between metal plates as may be seen from Fig. 6, while the movement of the yokes 13 in the longitudinal direction is limited by stops 20 which are covered with rubber on their sides turned towards the yokes.

The vibration dampers 21 which thus consist of rubber springs subjected to and resisting shearing stresses in a plane at right-angles to the shaft of the roller drum, are not tensioned and are so dimensioned that they possess greater rigidity in the longitudinal direction of the roller frame than in the vertical direction so that they can take up the tractive force.

A shaft 12 is provided with eccentric parts 12' adjacent to its end, for reasons discussed in detail hereinafter, which are journaled in bearings 12a in ends 2' of the drum 2.

The shaft 12, which is mounted in the yokes 13, serves as a driving shaft for the vibrators located inside the drum 2 and one end of the shaft 12 is for this purpose connected through a V-belt transmission to the motor 10. In order to compensate the pull of the V-belt that yoke 13 which is located nearest to the V-belt transmission 22 is influenced by a tension spring 23 placed between the

yoke and the frame 1. The V-belt is kept tensioned by means of tensioning devices which are not shown, since they are well-known per se.

Inside the roller drum 2 there are arranged two vibrator units working synchronously and mounted in axially spaced relationship. These two units are identical and consist of a roller track 25 mounted on an inwardly directed flange 26 in the drum 2. The roller track 25 is provided on its inner side with a groove 28 which serves as a race for a ball 27 and has an arc-shaped or concave cross-section the arc having a somewhat larger diameter than the ball 27. The depth of the groove thus decreases progressively towards both sides of the roller track and the groove is consequently able to guide the ball 27 during its rolling motion as it is caused to lie against the roller track by centrifugal force. The ball 27 is entirely free and is propelled along the roller track 25 by means of a driver 29 fixed to the shaft 12. The driver comprises a supporting ring 30 surrounding the ball 27, the inside of the said ring taking the form of a plain bearing surface facing the ball. When the ball is in contact with the roller track 25, said bearing surface will locally contact the ball peripherally and substantially at half its height. The supporting ring 30 is provided on two opposite sides with fixing projections 31 which are connected to the lower ends of two leaf springs 32 which are arranged parallel to one another and project radially from the part of the driver 29 surrounding the shaft 12. These leaf springs 32 are parallel to the running direction of the ball 27 and thus permit the transverse movement of the ring 30 relative to the roller track so that the ball can assume a suitable position in the groove of the roller track during its movement. The part of the driver 29 surrounding the shaft 12 takes the form of a clamping device gripping the shaft, the position of which can thus be regulated as required, and this part is provided with a U-shaped stop 33 which is turned towards the ball surrounded by the ring 30 and prevents the ball from falling out of the ring, if the shaft 12 stops in such a position that the ball is located at the highest point of the roller track 25. The ring 30, the shaft of which is substantially at right-angles to the driving shaft 12, the leaf springs 32 and their fixtures, are balanced by constructing that part of the driver which is diametrically opposed to the driving shaft 12 in the form of a counterweight 34 so that the shaft 12 is not subjected to vibrations due to its own unbalance. The vibrations are generated by the ball 27 which is driven along the roller track 25 and the weight of which is taken up directly by the roller track so that the vibrations are transmitted through the flanges 26 to the cover of the roller drum 2.

Since the driving shaft 12 for the vibrators serves at the same time as a bearing shaft for the drum 2, appreciable vibration stresses would be set up in all bearings if the drum were mounted concentrically on the shaft 12 as the vibrations would then be transmitted undamped to the yokes 13 and would act indirectly on the whole of the roller frame 1. This is avoided by mounting the drum 2 with its ends 2' on eccentric parts 12' of the driving shaft 12. The centre line of the eccentric parts is displaced relatively to the centre of the rotary shaft 12 in a direction diametrically opposed to the position of the balls 27 determined by the drivers 29, and the cen-

tricity of the parts 12' is adapted to the drum's amplitude of vibration in such a way that the drum and the driving shaft 12 form a dynamically balanced system in which the shaft 12 will remain substantially at rest in spite of the vibratory movements of the drum 2 produced by the balls 27. The frequency of vibration is of course determined by the speed of rotation of the driving shaft 12. Since the projecting ends of the driving shaft 12 which support the yokes 13 thus remain practically stationary, the bearings of the roller will be subjected to very small stresses from the vibrations, and they will thus be better suited to take up the stresses which occur when the roller is drawn forward over the surface which has to be worked on.

15 The invention, is not, of course, limited to the construction shown by way of example. Thus, for example, the roller may be provided with two or more vibrating roller drums, in a common frame, and the vibration generators in said drums may be driven by a common motor. 20 Furthermore, the vibrator units illustrated and described may also be employed for other purposes than for setting roller drums in vibration.

What I claim is:

1. A vibratory roller mechanism comprising a cylindrical roller drum, bearings in the ends of the drum, a driven rotatable shaft extending through and rotatably supported by the bearings in the roller drum, a grooved raceway supported from the inner periphery of the drum, said raceway being concentric with the drum and spaced from the shaft, a ball weight rotatably supported in the raceway groove; a driver for the ball including a member connected to the shaft, a ring surrounding the ball, and spring members joining the ring to the member and supporting the ring rigidly against movement along the raceway groove and resiliently against movement parallel to the raceway axis; whereby rotation of the shaft causes the ball to travel along the raceway and directly vibrate the drum.

2. A vibratory roller mechanism as defined in claim 1, in which a frame is journaled to the ends of the shaft, and eccentric journals having a common axis displaced from the shaft axis in a direction opposite to that of the ball are formed on the shaft at the drum bearings to reduce vibrations transmitted to the frame.

45 3. A vibratory roller mechanism as defined in claim 1, in which a frame is resiliently suspended from the ends of the shaft, and means connecting the frame and each end of the shaft include a bearing on the shaft, a yoke rigidly secured to the bearing, a vertically acting spring coupling the yoke to the frame, and rubber elements fastened to relatively movable parallel surfaces on the yoke and the frame, said rubber elements resisting vertical shearing forces set up by the vibrating drum to absorb and cushion them.
